UNITED STATES PATENT OFFICE.

CHARLES WESLEY TAYLOR, OF NEW YORK, N. Y.

MEDICAL BATTERY.

No. 858,117.

Specification of Letters Patent.

Patented June 25, 1907.

Application filed December 22, 1905. Serial No. 292,938.

To all whom it may concern:

Be it known that I, CHARLES WESLEY TAYLOR, a citizen of the United States, and a resident of the city of New York, borough of Manhattan, in the county and State of New York, have invented a new and Improved Medical Battery, of which the following is a full, clear, and exact description.

The invention relates to medical and surgical electricity, and its object is to provide a new and improved medical battery which is simple and durable in construction, exceedingly compact, and arranged for hand use, to enable a person to conveniently apply the apparatus to any part of the body or move it over any area of the body, to cause a current of electricity to pass, by way of the hand holding the apparatus, to the body-part on which the device is applied at the time.

The invention consists of novel features and parts and combinations of the same which will be more fully described hereinafter and then pointed out in the claims.

A practical embodiment of the invention is represented in the accompanying drawings forming a part of this specification, in which similar characters of reference indicate corresponding parts in all the views.

Figure 1 is a face view of the improvement, one of the covers being removed; Fig. 2 is a transverse section of the same, on the line 2—2 of Fig. 1; Fig. 3 is an edge view of the same, parts being shown in section; Fig. 4 is a diagrammatic view of the improvement; Fig. 5 is a transverse section of one of the covers provided with a brush attachment, the section being on the line 5—5 of Fig. 6; Fig. 6 is a face view of the same; and Fig. 7 is a transverse section of one of the covers provided with a sponge attachment.

The casing of the medical battery is formed of an open annular frame A made of hard rubber or other suitable insulating material, and of covers B and C made of metal and forming electrodes to contact with parts of the human body, either or both of the covers being shaped to form a handle adapted to be taken hold of by the user, to manipulate the medical battery as hereinafter more fully described. A dry battery D is located within the casing and is removably secured to the frame A, to permit of replacing a rundown battery by a new one whenever it is necessary to do so. For the purpose men-

tioned, one end of the battery D rests on the free ends of a curved spring E, secured at its middle by screws E' to the end A' of the frame A; and the core D' projecting from the other end of the said battery D fits a socket F secured by screws F' to the end A² of the frame A.

An induction coil G is secured to the side A³ of the frame A and is provided, at one end, with a suitable vibrator H and in the other end of the said induction coil is held a shiftable sleeve I for regulating the strength of the current to be applied to the body of the user. The outer end of the sleeve I is provided with an arm I' extending through a slot A⁴ formed lengthwise in the side A³ of the frame A, and on the outer end of the arm I' is secured a knob or button I², adapted to be taken hold of by the user of the apparatus, to move the sleeve I out of or into the induction coil G to regulate the strength of the current to be used, the strength of the current being indicated by the position of the knob I² on a graduation J formed on the outer face of the side A³ of the frame A (see Fig. 3.)

The arm I' is adapted to pass between switch contact plates K and K' secured to the inner face of the side A³ of the frame A, and the contact plate K' is connected by a wire L with the socket F, and consequently to the battery D, while the other contact plate K is connected by a wire L' with the stationary member of the vibrator H, as plainly indicated in Fig. 4. The primary coil L² is connected with the battery at the set-screw E' and spring E, and is also connected with the movable member of the vibrator H, and the secondary or induction coil L³ has one end connected with a plug sleeve N held in the end A² of the frame A, while the other end of the secondary coil L³ is connected with a plug sleeve N' arranged in the end A' of the frame A. The plug sleeves N and N' are engaged by transverse pins O and O', in engagement at their outer ends with the covers B and C, respectively, as will be readily understood by reference to Figs. 1 and 2.

It is evident that when the arm I' moves between and in engagement with the contact plates K and K', then the circuit of the primary coil is closed, the vibrator H is actuated and the induced current in the secondary

coil L^3 passes to the covers B and C. Now, as the operator has hold of the frame and of one of the covers with one hand and places the other cover in contact with any part of the body, it is evident that a current passes from the hand holding the cover to the part of the body in contact with the other cover, and consequently the desired curing effect can be produced on any afflicted part, as the operator can move the cover in contact with any part of the body, it being understood that the two covers B and C form electrodes in contact with the user's body at separated portions.

15 The contact plate K is preferably somewhat longer than the contact plate K' (see Fig. 2); that is, the contact plate K is extended toward the induction coil G to form a temporary yielding stop for the arm I' 20 when the user first pushes the knob I^2 , thus indicating to the user that the knob I^2 must be pushed farther in in order to switch in the current. Normally the arm I' is out of engagement with the contact plates K and K' , 25 and consequently the medical battery is inactive.

If desired, the usual plugs on insulated wires carrying handles may be connected with the plug sleeves N and N' , thus enabling 30 the user to employ the device for other purposes, the current in this case passing by way of the insulated wires to the object instead of by way of the covers B and C.

In order to securely hold the covers B and 35 C in place, the covers are preferably in dish form and their edges are sprung over annular flanges A^5 and A^6 formed on the opposite faces of the frame A, as will be readily understood by reference to Figs 1 and 2. If 40 desired, one of the covers (as shown in the drawings, the cover B) is provided with studs B' for removably holding a metallic brush back P in engagement with the outer face of the cover B, the said brush back being 45 provided with suitable metallic bristles P' , adapted to be used as the electrode, to be moved in contact with the human body. In a like manner the studs B' may be engaged by a metallic back Q carrying a moistened 50 sponge Q' , to be used as an electrode for contact with the human body. The sponge Q' is fastened by stitches Q^2 or other fastening means to the metallic back Q. It is understood that in either of the cases mentioned 55 the user takes hold with one hand of the cover C and brings the metallic brush-bristles P' or the sponge Q' in contact with the afflicted part. In order to prevent possible short-circuiting, the inner faces of the 60 covers B and C are preferably provided with linings V^2 , C' of paper, canvas or other insulating material.

The apparatus shown and described is

exceedingly compact, extremely light, and can be readily manipulated by the user to 65 reach any desired part of the body, either by mere contact or by brushing and sponging.

Having thus described my invention, I claim as new and desire to secure by Letters 70 Patent:—

1. A medical battery comprising a frame of insulating material and having covers on opposite sides for forming electrodes, a battery mounted in the said frame, an induction coil, mounted in the said frame, the battery and induction coil being electrically connected 75 with each other and with the said covers.

2. A medical battery comprising an annular frame of a non-conducting material and having covers on opposite sides for forming electrodes, a battery mounted in the said frame, an induction coil mounted in the said frame, the battery and coil being electrically 80 connected with each other and with the said covers, and manually controlled means for regulating the power of the electrical current.

3. A medical battery comprising a frame of insulating material and having covers on 85 opposite sides for forming electrodes, a battery mounted in the frame, an induction coil, mounted in the frame, the battery and induction coil being electrically connected with 90 each other and with the said covers, either 95 of said covers forming a handle to be taken hold of by one hand of the user to bring the other cover in contact with another part of the body.

4. A medical battery comprising a frame 100 of insulating material and having covers on opposite sides for forming electrodes, a battery mounted in the said frame, an induction coil, mounted in the frame, the battery and induction coil being electrically connected 105 with each other and with the said covers, one of the covers forming a handle to be taken hold of by one hand of the user to manipulate the device and bring the other cover in engagement with another part of the body of 110 the user.

5. A medical battery comprising a frame of insulating material and having covers on opposite sides for forming electrodes, a battery mounted in said frame, an induction coil, mounted in the frame, the battery and induction coil being electrically connected with each other and with the said covers, one of the covers forming a handle to be taken hold of by one hand of the user to manipulate the device, the other cover being provided with a removable device forming an electrode to engage another part of the body.

6. A medical battery comprising a frame of insulating material and having covers on 125 opposite sides for forming electrodes, a bat-

tery, an induction coil, the latter and the battery being arranged within the said frame and electrically connected with each other and with the said covers, one of the covers forming a handle to be taken hold of by one hand of the user to manipulate the device, the other cover being provided with a removable attachment forming an electrode to engage another part of the body, and a regulator for the current arranged within the frame and having a handle extending through a slot in the frame to the outside thereof, to be within convenient reach of the user.

7. A medical battery comprising a frame of insulating material and having covers on opposite sides for forming electrodes, a battery, an induction coil, the latter and the battery being arranged within the said frame and electrically connected with each other and with the said covers, one of the covers forming a handle to be taken hold of by one hand of the user to manipulate the device, the other cover being provided with a removable attachment forming an electrode to engage another part of the body, a sleeve movable in the coil and having a handle, and contact plates adapted to be engaged by the said handle, to electrically connect the plates and switch in the current, the said handle extending through a slot in the frame to the outside thereof.

8. A medical battery comprising a frame of insulating material and having covers on opposite sides for forming electrodes, a battery, an induction coil, the latter and the battery being arranged within the said frame and electrically connected with each other and with the said covers, one of the covers forming a handle to be taken hold of by one hand of the user to manipulate the device, interchangeable brush and sponge attachments for removable attachment to the other cover to engage another part of the body, a sleeve movable in the coil to regulate the strength of the current, the said sleeve having a handle, and contact plates adapted to be engaged by the handle to switch in the current, the said handle extending through a slot in the frame to the outside thereof, one of the said contact plates being extended beyond the other to form a yielding stop.

9. A medical battery comprising a frame of insulating material having interchangeable covers forming the electrodes, generating means within the said frame, plug sleeves carried by the frame and electrically connected with said generating means, and means for electrically connecting the said covers with the plug sleeves when the covers are in position on the frame.

10. A medical battery comprising a portable casing having interchangeable covers forming the electrodes, generating means

within the said casing and connected with the said covers, and means inside the casing for regulating the force of the generated electric current, the said means also forming part of a switch for throwing the electric current on or off and having a controlling member extending to the outside of the casing to be under the control of the user.

11. A medical battery comprising an annular frame of a non-conducting material and having covers on opposite sides for forming electrodes, a battery mounted in the said frame, an induction coil mounted in the said frame, the battery and coil being electrically connected with each other and with the said covers, and manually controlled means for regulating the power of the electrical current, the said means also forming part of a switch for throwing the electric current on or off.

12. A medical battery provided with an induction coil, a movable sleeve for the same, switch contacts, and means connected with the movable sleeve and adapted to engage the switch contacts and to be disengaged therefrom to throw the electric current on or off.

13. A medical battery comprising a frame of insulating material and having covers on opposite sides for forming electrodes, a battery, an induction coil, the latter and the battery being arranged within the said frame and electrically connected with each other and with the said covers, and interchangeable brush and sponge attachments for removable attachment to one of the covers.

14. A medical battery comprising a frame of insulating material and having covers on opposite sides for forming electrodes, a battery, an induction coil, the latter and the battery being arranged within the said frame and electrically connected with each other and with the said covers, a movable sleeve in the said induction coil having a handled arm extending to the outside of the frame, and switch plates adapted to be engaged by the said handled arm to throw the electric current on or off.

15. A medical battery comprising an open frame of insulating material, a battery mounted in said frame at one side and between the ends of the frame, the battery being removably secured to the frame, an induction coil mounted in the frame at the other side, and covers on opposite faces of the frame for forming electrodes, the said battery and induction coil being electrically connected with each other and with the said covers.

16. A medical battery comprising a frame of insulating material, a battery mounted in said frame, an induction coil mounted in the frame, plug sleeves arranged in the ends of said frame, transverse pins in the ends of the

frame and engaging at their inner ends the
5 plug sleeves, covers on opposite faces of the
frame for forming electrodes, each cover
when in position engaging the outer end of
one of said pins, and electrical connections
between the battery and induction coil and
between the latter and the said plug sleeves.

In testimony whereof I have signed my
name to this specification in the presence of
two subscribing witnesses.
